TIGHTENING REEL FOR CLOTHESLINES

Carroll W. Baty, Tarzana, Calif.

Application April 30, 1951, Serial No. 223,807

1 Claim. (Cl. 254—164)

1
This invention comprises novel and useful improvements in an adjustable support for clotheslines and is directed to similar subject matter and represents an improvement over the invention set forth in my copending application, Serial No. 187,299, filed September 28, 1950, for Clotheslines.

The principal objects of this invention are to provide an improved supporting device for clotheslines which will enable a plurality of clotheslines to be mounted in an improved manner and will generally facilitate the adjustment of the tension thereof; will enable all of the clotheslines to be simultaneously tensioned by a common tightening mechanism; and will permit the individual tensioning and varying of the tension of individual clotheslines without interfering with the above mentioned simultaneous tensioning of the lines.

A still further object of the invention is to provide a clotheslines adjusting and supporting mechanism in which individual mounting and tensioning assemblies are applied to one end of the individual clotheslines, and a simultaneous tensioning mechanism is provided for engaging the other ends of the clotheslines.

Yet another object of the invention is to provide a clotheslines tension adjusting mechanism having a ratchet operating mechanism provided with a readily disengageable handle; and having individual tensioning shafts for the foot ends of the clotheslines, together with improved means for maintaining the tensioning shafts in adjusted position.

These, together with various ancillary features and objects of the invention, which will later become apparent as the following description proceeds, are attained by the present invention, a preferred embodiment of which has been illustrated, by way of example only, in the accompanying drawings, wherein:

Figure 1 is a fragmentary perspective view showing the elements of this invention applied to the horizontal foot supporting bar for a plurality of clotheslines, parts being broken away;

Figure 2 is a vertical transverse sectional view taken substantially upon the plane indicated by the section line 2—2 of Figure 1 and showing the locking means for the foot tensioning members of the clothesline;

Figure 3 is a perspective view of a portion of the horizontal head bar of the clothesline supporting and adjusting mechanism, parts being broken away; and

Figure 4 is a detail exploded perspective view

2
of the clamping means for detachably securing the handle to the ratchet mechanism.

The present invention is shown applied to the horizontal head and foot bars 10 and 12, respectively, each of which is mounted upon a vertical support shaft 14. As set forth in my above identified copending application, the clotheslines supporting assembly consists of the conventional arrangement of parallel vertical support bars 14 spaced from each other and provided with the horizontally disposed head and foot support bars 10 and 12, adapted to have stretched therebetween and adjustably secured thereto, as set forth hereinafter, a plurality of clotheslines 16, parallelly disposed.

The horizontal foot bar 12 is provided with a plurality of spaced apertures, through which the foot ends of the clotheslines 16 are adapted to extend and be attached to individual tensioning and anchoring members as set forth hereinafter. The forward or head ends of the clotheslines 16 are attached to chains or cables 18 which, in turn, are secured to and wound about a crank-shaft 20 which extends in parallel relation to the horizontal head bar 10. The clotheslines are thus all secured at one end to a common crankshaft 20, but are individually connected at their foot ends to individual mounting and tensioning members as set forth hereinafter.

Referring first to Figures 1 and 2, it will be seen that a plurality of U-shaped brackets 20 are provided having a parallel laterally extending end walls or lugs 22. U-bolts 24 are provided which extend through the base portions of the brackets 20 and serve to clamp the brackets in longitudinally adjusted position upon the tubular shaft constituting the horizontal foot bar 12. As will be readily understood, the base portions of the brackets 20 are necessarily provided with apertures which register with the apertures in the foot bar so that the clothesline 16 may extend through these apertures.

Rotatably journaled in the parallel end walls 22 of the brackets 20 is a slack take-up shaft 26 whose ends preferably extend beyond the bracket members 22 as shown. One such bracket and take-up shaft journaled therein is provided for each of the clotheslines 16. The latter have their foot ends wound upon the take-up shafts 26 and secured thereto in any desired manner whereby, upon rotation of the shafts, the individual clotheslines will be selectively tightened or loosened.

To effect this slack take-up and tensioning function, the opposite ends of the take-up shafts

55 26 are provided with diametrically disposed bores

28 disposed at suitable angular intervals about the shaft. Preferably, a pair of handles 30 are provided, slidably received within the bores 28, the handles at the opposite ends of the shaft being preferably disposed at an angular relation to each other, as, for example, at right angles, as shown in Figure 1. These handles may be provided with terminal knobs 32 to prevent their removal from the bores of the slack take-up shafts 26 but permit sliding movement through these bores.

In order to retain the slack take-up shafts in adjusted position, the foot bars 12 are provided with suitable apertures 34 therethrough into which the ends of the handles may be removably seated, as shown in Figure 2, to thereby lock or retain the take-up shafts in adjusted position.

Thus, the individual clotheslines may be adjustably tensioned as desired and the take-up shafts may be locked in the adjusted position in the manner apparent from Figure 2.

The crankshaft 28 has its ends journaled in supporting brackets, one of which, as shown in Figure 3, consists of an angle iron member having the portions 36 and 38, the former being secured by I-bolts to the head bar 10, and the latter constituting a bearing rotatably supporting the end of the crankshaft 20.

A ratchet operating mechanism is associated with the crankshaft and its mounting brackets. This mechanism includes an elongated plate 40 constituting a ratchet handle and which is freely rotatably received upon the crankshaft 28 adjacent the bracket plate 38. Fixedly secured to the crankshaft 20 is a ratchet gear 42, it being seen that the ratchet handle plate 40 is retained between the bracket wall 38 and the gear 42 for free oscillation upon the crankshaft. By means of a pivot 44 a ratchet pawl 46 is secured to the plate 40 and is operatively engageable with the teeth of the ratchet gear 42, a spring 48 being connected to the pawl 46 and to a supporting lug 50 on the plate 40. This spring serves to yieldingly retain the pawl 46 in engagement with the ratchet teeth whereby oscillation of the plate 40 in one direction will cause rotation of the shaft 20, but movement of the plate in the other direction will cause the pawl 46 to ride over the teeth of the gear 42. A locking pawl 52 has its nose engageable with the teeth of the pinion 42, and is pivotally mounted upon a pivot pin 54 carried by the bracket plate 38. The pawls 52 and 46 are oppositely disposed with respect to the gear 42, in such a manner that the rotation of the gear by the ratchet pawl 46 will cause the gear to slide under the locking pawl 52, while upon reverse movement of the ratchet pawl, the latter will slide over the gear teeth while the locking pawl will engage or prevent reverse rotation of the same. Thus, the ratchet mechanism will facilitate rotation of the crank shaft in one direction whereby all of the clotheslines will be simultaneously tensioned, but whereby release of this tension will be prevented.

In order to enable the tension to be released upon the clotheslines by permitting reverse rotation of the crankshaft 20, a common pawl release means is provided consisting of a wire or cable 56 adapted to be manually operated by the user and which is connected to a chain or other fastener 58. The latter has one end secured to the underside of the ratchet pawl 46 for withdrawing the same from its engagement

with the pinion teeth against the resistance of the spring 48, and has its other end entrained over a guide 58 in the form of an I-bolt carried by the bracket plate 36, and secured to the upper surface of the locking pawl 52. As will now be apparent, downward movement of the member 56 will disengage both pawls, thereby permitting the crankshaft to rotate and release the tension on the clotheslines.

As shown in Figures 3 and 4, a pair of channel-shaped clamping plates 62 and 64 are provided, each apertured at 66, for the reception of fastening members in the form of pins, bolts, rivets or the like. An extension handle 70 is adapted to be received removably in the socket formed between the two clamping plates 62 and 64 when the latter are clamped upon the extremity of the ratchet plate 40. If desired, the pin 68 may extend through suitable apertures in the members 40 and 70 as well as through the apertures 66 of the clamping plates, or may merely constitute means for retaining the clamping plates upon the member 40 if desired.

By the construction previously described, it will now be apparent that the ratchet mechanism provides a means for simultaneously tensioning or releasing the tension of the plurality of clotheslines supported by this device. However, individual clotheslines may have their tensions varied or separately adjusted by the slack take-up members previously described and mounted upon the foot bar of the device. This device, therefore, greatly conveniences the clothesline user by enabling him to vary the slack of a particular line as desired, or increase the tension of all of the lines or release the same with a single motion from a single position.

Where desired, the horizontal bars 10 and/or 12 may be detachably secured to the vertical surfaces of the posts 14 as by bolts, clamps or in any other desired manner. It will be appreciated that each end supporting assembly may include a pair of parallel posts 14 with the horizontal cross bars 10 or 12 bolted thereto, and each may include a single tightener assembly of the type shown in Figure 3 for all of the clotheslines together with a single member of the type shown in Figure 3 mounted on the opposite end supporting assemblies.

Since, from the foregoing, the construction and advantage of this device are readily apparent, further description is believed to be unnecessary.

However, since numerous modifications and equivalents will readily occur to those skilled in the art after a consideration of the foregoing specification and accompanying drawings, it is not intended to limit the invention to the exact embodiment shown and described, but all suitable modifications and equivalents may be resorted to which fall within the scope of the appended claim.

Having described the invention, what is claimed as new is:

A reel comprising a support, a shaft journaled in said support and adapted to receive a line wound thereon, a ratchet gear fixed to said shaft and rotatable therewith; a ratchet handle rotatably journaled on said shaft, a ratchet pawl pivoted to said handle and engaging said gear to cause rotation of said shaft in one direction, a locking pawl pivoted to said support and releasably engaging said gear to prevent reverse rotation, means for simultaneously releasing both said pawls, said means including a cable attached at its ends to said pawls and being slidably mount-

ed intermediate its ends above said pawls on said bracket, and an actuating means secured to said cable intermediate its ends for drawing the ends toward one another and releasing the pawls from the gear.

CARROLL W. BATY.
